(57) CLAIM

The ornamental design for a tub surround for a laundry
appliance, as shown and described.

DESCRIPTION

FIG. 1 is a top, front perspective view of a tub surround for
a laundry appliance showing my new design;

FIG. 2 is a top plan view shown on a reduced scale thereof;
FIG. 3 is a top, front perspective view shown on a reduced
scale thereof;

FIG. 4 is a left side elevation view shown on a reduced scale
thereof;

FIG. 5 is a right side elevation view shown on a reduced scale
thereof; and,

FIG. 6 is a front elevation view shown on a reduced scale
thereof.

The broken line showing of a laundry appliance is for
illustrative purposes only and forms no part of the claimed
design.
